LIQUID PRESSURE REMOTE CONTROL
SYSTEMEdward Claude Shakespeare Clench, London,
England, assignor to Automotive Products
Company Limited, London, EnglandApplication March 3, 1938, Serial No. 193,790
In Great Britain March 20, 1937

8 Claims. (Cl. 60—54.5)

This invention relates to liquid pressure remote control systems, and it has for its primary object to provide improvements in the known form of remote control system utilising a single pipe-line connection between the transmitter unit and the motor unit. Such systems are, of course, commonly used for the hydraulic actuation of brakes and in other instances where the transmitter and motor units automatically return to a predetermined position when the pedal, lever or other actuating member ceases to be restrained or operated. The improvements according to the present invention enable a very simple construction of single-acting liquid pressure remote control system to be produced for purposes where the actuating member of the transmitter unit must remain of its own accord at any position in which it may be set within its range of operative movement.

20 In a liquid pressure remote control system comprising a transmitter cylinder and piston having actuating means, a motor cylinder and piston, a single pipe line connecting said cylinders, and a return spring adapted to move the motor piston forward as the transmitter piston is retracted, the present invention is characterised by the provision of locking means which are automatically rendered operative by the action of letting go the actuating means.

30 The invention further provides a liquid pressure remote control system comprising a transmitter cylinder and piston having actuating means, a motor cylinder and piston, a single pipe line connecting said cylinders and a return spring adapted to move the motor piston forward as the transmitter piston is retracted, a lost motion device being provided between the actuating means and the transmitter piston, and an automatic locking device for said piston being released by the movement of the actuating means in taking up the lost motion at the commencement of a resetting operation. The locking device is preferably effectual to prevent movement of the transmitter piston in both directions except, of course, under the influence of the actuating means, while the transmitter piston can conveniently be acted upon by a spring which tends to move it forward and thus oppose the action of the spring of the motor piston with a view to rendering the system easier to operate. A hydraulic accumulator device is preferably provided to receive any working liquid expelled from the system due to a rise of temperature while the motor piston is in its fully retracted position, since the locking device prevents the transmitter piston from responding

to such an increase in volume. The motor piston, in reaching its extreme retracted position, may place the pipe line in communication with the hydraulic accumulator device by way of a non-return valve, the working space of the accumulator preferably being in permanent communication with the pipe line through another non-return valve whereby liquid forced into the accumulator device while the motor piston is in its fully retracted position can be discharged to the pipe line when the pressure in the latter falls, irrespective of the position of the motor piston.

5 The locking of the transmitter piston can conveniently be effected by a roller or equivalent member which is resiliently held between a pair of converging surfaces, one of which latter is fixed while the other is movable in unison with the transmitter piston. Thus, the transmitter piston may be moved by a pivoted member which carries one of the pair of converging surfaces, the other of said surfaces comprising an arcuate track arranged concentrically with regard to the pivotal axis of the pivoted member. The actuating means may carry a releasing member which urges the roller or equivalent out of engagement with the converging surfaces so as to release the locking means and may comprise a handle which is mounted for arcuate movement about the same axis as the pivoted member, with which latter it is connected by a lost motion device.

20 The invention is illustrated in the accompanying drawings in which

Figure 1 is a sectional elevation of the preferred transmitter and motor units;

25 Figure 2 is a sectional side elevation of the transmitter unit taken on the line 2—2 of Figure 1;

Figure 3 is a fragmentary sectional plan taken on the line 3—3 of Figure 1;

30 Figures 4 and 5 are enlarged diagrammatic views of the locking device in its locked and unlocked positions respectively; and

Figure 6 is a sectional side elevation through the motor unit taken on the line 6—6 of Figure 1.

35 The remote control system illustrated, which is primarily intended for regulating the throttle of a marine engine but which can obviously be used for many other purposes, comprises a transmitter unit indicated generally at A and a motor unit B, these being connected together by a single pipe line 10 adapted for the transmission of liquid under pressure.

40 A casing 11 forms the body of the transmitter unit A, and carries a casting comprising a combined reservoir 12 and transmitter cylinder 13. 45

A transmitter piston 14, which is substantially tubular in form except for a web 15, is slidably mounted within the cylinder 13 and is actuated by means of a connecting rod 16 pivoted to a bracket 5 17 secured to the web 15. At its other end the connecting rod 16 is bifurcated, as will be seen more clearly in Figure 2, and is connected by means of a pin 18 to a pivoted rocking member 19. The latter is freely rotatable upon a fixed 10 tubular spindle 20 carried by the casing 11 and comprises a pair of side plates 21 and 22, both of which latter are extended downwardly as will be seen in Figures 1 and 2 so as to carry a pin 23, by which the pivoted member 19 is connected 15 with a rod 24. This is slidably mounted within a tube 25 abutting against a plate 27 in the casing 11 through the medium of a ball 26, said tube 25 and rod 24 being fitted with radial flanges 28 and 29 respectively for the accommodation of a pair 20 of coiled compression springs 30 and 31.

The plate 21 is also extended towards the left as indicated at 21a in Figures 1 and 3, and carries a block 32 which is used for locking the pivoted member 19 and consequently the transmitter piston 14 at any position or setting within its range of movement. A curved track 33 is carried by the casing 11 and has an internal surface 34 which is concentric with the spindle 20, but the block 32 has its adjacent surface 35 30 shaped to a greater curvature than the surface 34 or else is cut away at its outer corners so that the surfaces 34 and 35 converge in a direction towards the centre radial line of the block 32, as will be seen more clearly in Figures 4 and 5. 35 A pair of rollers 36 and 37 are carried upon the block 32 by laminated spring fingers 38 and are urged thereby into the space between the converging surfaces 34 and 35 of the track 33 and block 32 respectively. This, of course, produces a locking action and normally prevents movement of the block 32 in either direction, since such movement causes one or other of the rollers 36 and 37 to become more firmly jammed between the said converging surfaces 34 and 35.

40 In order to reset the transmitter piston 14 i. e. to change its setting or position within its range of movement, a handle 40 extends through an arcuate slot 41 in the rounded end of the casing 11 and is formed at its lower extremity with a boss 42 which is freely rotatable upon the centre portion 43 of the pivoted member 19. The boss 42 has a lug 44 which is formed with a hole 47 embracing the pin 18 with a relatively large amount of clearance. The boss 42 is also extended as indicated at 45 in Figures 1 and 3 and carries an L-shaped releasing member 46, the extremity of which is positioned between the two rollers 36 and 37 as will be seen more clearly in Figures 4 and 5. Thus, when the handle 40 is moved in either direction the initial movement which takes up the play between the hole 47 and the pin 18 also causes the releasing member 46 to press one or other of the rollers 36 and 37 out of engagement with the converging surfaces 34 and 35 so that, when the lost motion between the hole 47 and pin 18 has been taken up, any further movement imparted to the handle 40 is transferred by the pin 18 to the pivoted member 19. Figure 5 shows the action which takes place when the handle 40 is moved in an anti-clockwise direction to retract the transmitter piston 14. It will be appreciated that, although the roller 37 has not been released, it is quite ineffectual in preventing the anti-clockwise movement of the block 32, and it merely

slips upon the surface 34. When the operator lets go of the handle 40 the roller 36 is once again forced between the surfaces 34 and 35 by means of the corresponding spring arm 38, thus returning the handle 40 to a slight extent. The slot 41 is closed by a sliding arcuate shutter 48 which moves with the handle 40 and is held in position by a light spring 49 carried by said handle. 5

The reservoir 12 normally contains a supply of liquid which is inserted by removing a filler cap 50, and the lower part of said reservoir extends completely round the transmitter piston 14 in the form of an annular passage 51 as seen in Figure 1. Thus, when the transmitter piston 14 is in its completely retracted position a number of small holes 52 in the forward end of the piston are brought into register with the passage 51, thus placing the pipe line 10 automatically into communication with the interior of the reservoir 12. Packing rings 53 and 54 prevent leakage of liquid along the piston, and a bleed plug 55 is incorporated in the cylinder 13 for the purpose of removing air when the system is being 20 filled with liquid. 25

In the motor unit B a casing 60 is fitted with a motor cylinder 61 having a slidably mounted motor piston 62 which is identical in construction to the transmitter piston 14. This piston is coupled by a connecting rod 63 with a pivoted 30 lever 64 which comprises two plates 65 and 66, as will be seen in Figure 6, and is securely carried by a spindle 67. Externally of the casing 60 this spindle is secured to an arm 68, which is mechanically connected to the throttle (not shown) or any other device which it is desired to operate from a distance. For effecting the forward movement of the motor piston 62 the lower end of the lever 64 is acted upon by a pair of coiled compression springs 69 and 70 which 40 are supported by a telescopic link comprising a pin 71 and tube 72 corresponding in construction to the parts 24 and 25 of the transmitter unit A. The motor cylinder 61 carries packing rings 73 and 74 and is formed between these with an annular passage 75. This, as shown in Figure 1, communicates with the pipe line through holes 76 in the piston when the latter is in its fully retracted position. Formed in one with the motor cylinder 61 is a hydraulic accumulator device 50 comprising a cylinder bore 77 accommodating an accumulator piston 78 which is normally forced to its end position as shown by means of a coiled compression spring 79. A slight projection 80 is formed on the piston 78 so as to ensure that 55 pressure liquid passing from the annular passage 75 through a non-return ball valve 81 can act upon substantially the whole area of the piston 78. A passage 82 leads from the space 83 in front of the piston 78, past a non-return ball valve 84 and communicates with the pipe line 10 by way of a passage 85, so that whenever the space 83 contains liquid at a pressure greater than that in the pipe line said liquid can be discharged through the non-return valve 84. The 60 purpose of the accumulator device 77, 78 is to avoid an excessive rise of pressure in the event of the volume of the working liquid increasing (due for example to a rise in temperature) while the parts are in the position shown in Figure 65 1. It will be appreciated that under these conditions the motor piston 62 is at the end of its travel and cannot move any further since the telescopic link 71, 72 is fully shortened. If, therefore, an expansion occurs in the working liquid 70 75

within the pipe line 18 the transmitter piston 14 is unable to give way owing to the locking rollers 36 and 37, so that a quantity of liquid corresponding to the expansion is forced past the ball valve 81 in the motor cylinder 61 and finds accommodation within the space 83 by compressing the spring 79. When at some later time the pressure in the pipe line 18 decreases, due for example to cooling, then the liquid from the space 83 is automatically returned by the piston 78 through the passages 82 and 85.

In the improved remote control system the primary function of the compression spring assembly 69, 70 is to move the motor piston 62 in a forward direction as soon as working liquid is withdrawn through the pipe line 18 owing to the operation of the handle 40 to retract the transmitter piston 14. Thus, the spring assembly 69, 70 creates and maintains a pressure in the working liquid except when the motor piston 62 has reached its extreme forward position where it comes into mechanical contact with the end of the motor cylinder 61. When this occurs, however, the transmitter piston 14 is retracted as far as possible and the holes 52 are in communication with the interior of the reservoir 12 so that the whole system is allowed to "breathe" at this particular setting, thus ensuring that the pipe line 18 and the working spaces of the cylinders 13 and 61 are full of liquid at atmospheric pressure. In the case of a remote control for working an engine throttle this breathing and rephasing position preferably corresponds to the "off" position of the throttle. The spring assembly 30, 31 in the transmitter unit cannot consistently produce liquid pressure in the system owing to the action of the locking device, but is incorporated to counteract the effect of the spring assembly in the motor unit and thus considerably reduce the amount of effort which is required to operate the lever 48.

The springs employed in the transmitter and receiver units may be made so as to have variable rates in order to compensate substantially for the change in the moment which they exert about the pivots of the respective lever arms due to the changes in the angular positions of the latter. This may be done by making the coils of the spring of varying stiffness and/or pitch so that a predetermined portion will first become coil-bound, and the rate of the spring will thus be increased.

What I claim is:

1. A liquid pressure remote control system comprising a transmitter cylinder and piston, a motor cylinder and piston, a spring urging said motor piston towards its fully advanced position, a single pipe line connecting the transmitter cylinder with the motor cylinder, a rocking member connected with the transmitter piston, angularly movable actuating means connected operatively with the rocking member by a lost motion connection, and locking means for preventing movement of the transmitter piston, except under the influence of the actuating means, said locking means comprising a pair of converging surfaces, one upon the rocking member and one fixed in relation to the transmitter cylinder, said fixed surface being concentric with the axis upon which the rocking member moves, a wedging member arranged to jam between said surfaces, resilient means urging said wedging member towards its jammed position, and means to disengage the wedging member from the surfaces during the movement required to take up the lost

motion between the actuating member and the rocking member.

2. A liquid pressure remote control system comprising a transmitter cylinder and piston, a motor cylinder and piston, a spring urging said motor piston towards its fully advanced position, a single pipe line connecting the transmitter cylinder with the motor cylinder, a rocking member connected with the transmitter piston, angularly movable actuating means connected operatively with the rocking member by a lost motion connection and arranged to move about the same axis as the rocking member, and locking means for preventing movement of the transmitter piston, except under the influence of the actuating means, said locking means comprising a pair of converging surfaces, one upon the rocking member and one fixed in relation to the transmitter cylinder, said fixed surface being concentric with the axis upon which the rocking member moves, a roller arranged to jam between said surfaces, resilient means urging said roller towards its jammed position, and means upon the actuating member arranged to disengage the roller from the surfaces during the movement required to take up the lost motion between the actuating member and the rocking member.

3. A liquid pressure remote control system comprising a transmitter cylinder and piston, a motor cylinder and piston, a spring urging said motor piston towards its fully advanced position, a single pipe line connecting the transmitter cylinder with the motor cylinder, a rocking member, angularly movable actuating means connected operatively with the rocking member by a lost motion connection, said rocking member being formed with a pair of radial arms, a connection from one of said arms to the transmitter piston, resilient means acting upon the other arm of the rocking member to retract the transmitter piston and locking means for preventing movement of the transmitter piston, except under the influence of the actuating means, said locking means comprising a pair of surfaces arranged side by side, one upon the rocking member and one fixed in relation to the transmitter cylinder, said fixed surface being concentric with the axis upon which the rocking member moves and the other being shaped so that both its end portions converge in relation to the said concentric surface, a pair of rollers arranged to jam in opposite directions between the said surfaces, resilient means urging said rollers towards their jammed positions, and means upon the actuating member arranged to disengage either one of the rollers from the surfaces during the movement required to take up the lost motion between said actuating member and the rocking member.

4. A liquid pressure remote control system comprising a transmitter cylinder and piston, a motor cylinder and piston, a spring urging said motor piston towards its fully advanced position, a single pipe line connecting the transmitter cylinder with the motor cylinder, a rocking member connected with the transmitter piston, angularly movable actuating means connected operatively with the rocking member by a lost motion connection and arranged to move about the same axis as the rocking member, and locking means for preventing movement of the transmitter piston, except under the influence of the actuating means, said locking means comprising an arcuate concave surface secured rigidly in relation to the transmitter cylinder and disposed concentrically with the mounting axis of the rocking member.

an arm formed on said rocking member and directed towards said arcuate surface, the extremity of said arm being curved to a relatively small radius so that its center part lies nearer to the 5 arcuate surface than its end parts, rollers interposed between said end parts and the arcuate surface, resilient tongues supporting said rollers and urging them towards one another so as to lock the rocking member against movement in 10 both directions, and disposed between said rollers a projection which is secured to the actuating means and which pushes either one of the rollers out of engagement with the two surfaces while 15 said actuating member moves to take up the lost motion between it and the rocking member.

5. A liquid pressure remote control system comprising a transmitter cylinder and a piston therein, actuating means for the piston, a motor cylinder and piston therein, a single pipe line 20 connecting said cylinders, a return spring to move the motor piston forward as the transmitter piston is retracted, a lost motion device between the actuating means and the transmitter piston, resilient means urging the actuating 25 means to a central position with respect to the lost motion device, an automatic locking device for locking said transmitter piston against movement in both directions, the movement of the actuating means in either direction when taking 30 up the lost motion at the commencement of a resetting operation releasing the automatic locking device, said locking device including opposed members each of which is resiliently held between a pair of converging surfaces, one of said 35 surfaces being fixed and the other movable in unison with the transmitter piston.

6. A liquid pressure remote control system comprising a transmitter cylinder and piston, actuating means for the piston, a motor cylinder and piston, a single pipe line connecting said cylinders and a return spring adapted to move the motor piston forward as the transmitter piston is retracted, a lost motion device between the actuating means and the transmitter piston, an 45 automatic locking device for normally preventing said piston being moved by the liquid in the direction in which it is moved by the actuating means, the movement of the actuating means in taking up the lost motion at the commencement of a resetting operation releasing the automatic locking device, said locking device including a roller or equivalent member which is resiliently held between a pair of converging surfaces, one of said surfaces being fixed and the other being movable in unison with the transmitter piston, the transmitter piston being moved by a pivoted member which carries one pair of converging surfaces, and the other of said surfaces

comprising an arcuate track arranged concentrically with regard to the pivotal axis of the pivoted member.

7. A liquid pressure remote control system comprising a transmitter cylinder and piston, actuating means for the piston, a motor cylinder and piston, a single pipe line connecting said cylinders and a return spring adapted to move the motor piston forward as the transmitter piston is retracted, a lost motion device between the actuating means and the transmitter piston, an automatic locking device for normally preventing said piston being moved by the liquid in the direction in which it is moved by the actuating means, the movement of the actuating means in taking up the lost motion at the commencement of a resetting operation releasing the automatic locking device, said locking device including a roller or equivalent member which is resiliently held between a pair of converging surfaces, one of said surfaces being fixed and the other being movable in unison with the transmitter piston, the actuating means carrying a releasing member which urges the roller or equivalent out of engagement with the converging surfaces so as to release the locking means, the actuating means comprising a handle mounted for arcuate movement upon the same axis as the pivoted member, being connected with said member by a lost motion device.

8. A liquid pressure remote control system comprising a transmitter cylinder and piston, actuating means for the piston, a motor cylinder and piston, a single pipe line connecting said cylinders and a return spring adapted to move the motor piston forward as the transmitter piston is retracted, a lost motion device between the actuating means and the transmitter piston, an automatic locking device for normally preventing said piston being moved by the liquid in the direction in which it is moved by the actuating means, the movement of the actuating means in taking up the lost motion at the commencement of a resetting operation releasing the automatic locking device, said locking device including a roller or equivalent member which is resiliently held between a pair of converging surfaces, one of said surfaces being fixed and the other being movable in unison with the transmitter piston, movement being imparted to the transmitter piston by a pivoted member having a pair of substantially diametrically opposed arms, one of which is coupled to the transmitter piston by a connecting rod and the other of which is acted upon by a coiled compression spring.

EDWARD CLAUDE
SHAKESPEARE CLENCH.
